Des. 232,172
Patented July 23, 1974

232,172

HINGED FREE-STANDING PARTITION

Steve Themis, 130 9th St., San Francisco, Calif. 94103

Filed June 14, 1971, Ser. No. 152,743

Term of patent 14 years

Int. Cl. D25—02
U.S. Cl. D13—1 K

FIG. 1.

FIG. 2.

FIG. 3.

FIG. 4.

FIG. 1 is a front view perspective showing my new hinged free-standing partition;

FIG. 2 is a top plan view;

FIG. 3 is a top plan view in the fully extended position; and

FIG. 4 is a side elevational view in the fully extended position, both sides being substantially identical.

I claim:

The ornamental design for a hinged free-standing partition, as shown and described.
